TWO-CYCLE DOUBLE-ACTING ENGINE

Robert L. Wilkins, Indianapolis, Ind.

Application February 18, 1950, Serial No. 144,945

5 Claims. (Cl. 123—61)

1

This invention relates to a dual acting internal combustion engine.

The chief object of the present invention is to provide a simple, compact engine structure that is symmetrical and wherein oppositely disposed parts are substantially identical.

One feature of the invention resides in utilizing the piston rod as a valve control.

A second feature of the invention resides in duplicating certain of the parts.

A third feature of the invention resides in providing a single piston within a cylinder and arranging same so that for any given fuel setting the force of the explosion is the same, that is, the unit force exerted upon the opposite faces of the piston by successive explosions is equal.

As indicated above, the present invention, like similar acting two-cycle dual engines, provides a power impulse for each movement of the power piston.

Other objects and features of the invention will be set forth in greater detail hereinafter.

The full nature of the invention will be understood from the accompanying drawings and the following description and claims.

In the drawings:

Fig. 1 is a central sectional view through a single cylinder embodiment of the invention.

Fig. 2 is a sectional view through an electrically controlled valve embodiment.

Fig. 3 is a vertical sectional view of a modified form of the invention wherein the piston rod, while utilized for valve control extends through but one of the cylinder heads.

Fig. 4 is a similar view of a similar but further modified form, the modification herein comprising an internal coolant control, also piston rod operable.

In Fig. 1 of the drawings, 10 indicates a cylinder water jacketed at 11. This is suitably and detachably supported by crank case 12 having guide way 13 therein for slidable accommodation of crosshead 14. To the same is pivotally connected at 15 one end of connecting rod 16, the other end of which is pivotally carried by crank portion 17 of crank shaft 18 suitably supported in crank case bearings such as schematically illustrated at 19. A pan 20 closes the case.

The upper end of cylinder 10 has suitably attached thereto upper head 21 water jacketed at 22. The lower end of cylinder 10 has suitably attached thereto in depending relation lower head 23 water jacketed at 24. These heads are identical so a description of one will suffice for both.

Each head includes an intake passage 25 for 55

2

connection to a suitable fuel supply source not shown. Poppet valve 26 controls the intake and has stem 27 projecting outwardly and mounting closing spring 28 retained on and concentric with said stem by retainer 29 of any suitable character.

The head includes the firing chamber 30 and the spark plug 31 is mounted in the head opening 32 provided for that purpose. The head also includes the piston rod bore 33 provided with 10 rings 34 for sealing the rod 35.

Herein rod 35 extends through the opposed heads and intermediately has suitably secured to it the double acting piston 36 mounting rings 37. The cylinder midway between its ends includes the exhaust ports 38 leading into the exhaust manifold 39. This may extend entirely around the cylinder and the exhaust ports may be similarly disposed, if desired.

The electrical circuit to the plugs is omitted 20 for clearness but each plug is energized at the proper time. Carried by each end of the piston rod 35 is a valve actuating arm 40. The cross-head 14 is suitably attached to the lower end of said rod 35.

25 Operation is as follows: When the piston uncovers the exhaust ports that end of the cylinder then communicating therewith exhausts the previously burned gases. At this time, or slightly before, depending on the length of the piston, the intake valve at the opposite end of the cylinder opens and supplies that end with fuel and air. As the piston continues its travel the first end of the cylinder through the piston continues to exhaust and the other end of the cylinder compresses the fuel and air, the intake valve thereto previously having closed. When this charge is compressed it is fired and the piston reverses its travel. The said first mentioned end of the cylinder is then charged as soon as exhaust ports are closed and the charge in said first end is then compressed and fired. If scavenging is desired the intake valves may be opened before the exhaust ports are closed. The expanded burned gases in said second end are exhausted as soon as the exhaust ports are uncovered by the piston and communicate with that end of the cylinder.

Hence for each stroke of the piston there is a power application to rod 35 and hence the rod is alternately subjected to a push and pull force which is equal because the rod extends through each head.

Reference will now be had to Fig. 2. In this form of the invention each valve is spring closed as before but herein the valve is opened by a

solenoid suitably energized and controlled by switch means. Such switch means may have an active element carried by rod for bridging contact to close and open the circuit to the solenoid. If preferred the valves may be solenoid controlled through a timing distributor similar to that utilized for energizing the plugs in timed relation.

In the form shown in Fig. 2 the piston rod 135 mounts upon the exposed portions elongated contact bridging portions 150. These twice bridge contacts 151 and 152 and close the circuit between lines 153 and 154. Disposed adjacent rod 135 and in the path of member 150 is a tilttable normally closed switch 155 connected in series with the aforesaid switch. Associated with the tilttable switch is a dashpot 156 and spring 157. The aforesaid is duplicated at opposite ends of the rod. The switch control at one end controls the solenoid 140 at the opposite end and in turn opens valve 126 constrained to closed position by spring 128. Stem 127 mounts core 158.

Operation is as follows: At the predetermined time that the intake valve is to open switch 155 is closed and rod movement disposes portion 150 across contacts 151 and 152 to energize solenoid 158 to hold open the intake valve. Upon termination of intake duration this switch opens and stays open until the end of the piston stroke. During this interval the intake valve is closed.

Upon attainment of the end of the stroke member 150 opens switch 155 in opposition to spring 157. Upon return stroke, while spring 157 tends to close switch 155 the dashpot holds it open until member 150 passes beyond contacts 153—154. Thus selective control of the solenoids is attained.

When the aforesaid balanced type of structure is not desired or required, a crank shaft rotatable timer switch can be employed and successively energize the solenoids at predetermined times and for predetermined intervals.

In Fig. 3 there is illustrated a modified form wherein 236 indicates the piston with rings 237 slideable in the cylinder 210. The heads 221 and 224 are not identical but are similar. Herein stem 235 mounts arm 240 terminating in an angular end 240^a mounting a roller 260.

Mounted upon two fixed pivots 261 and 262 are rockers 263 and 264 respectively. Rocker 263 actuates stem 227 of lower valve 226, while rocker 264 actuates stem tappet rod 265 that actuates stem 227 of upper valve 226. Each rocker arm includes an angularly disposed free end 263^a and 264^a mounting rollers 263^b and 264^b respectively.

In the reciprocation of stem 235 roller 260 engages rollers 263^b and 264^b and vice versa. Upon the down stroke, see Fig. 3, rocker 263 is rocked clockwise for lower valve opening and rocker 264 is rocked clockwise which is without function. Upon the upward stroke rocker 264 is rocked counter-clockwise for upper valve opening and rocker 263 is similarly rocked without functioning. The position of pivots 261—262 can be adjusted up or down or towards or away from each other for proper valve timing.

Reference will now be had to Fig. 4 wherein a slightly modified form of the preceding type is illustrated. Numerals utilized herein are of the three hundred series. In this form piston rod 235 as before mounts valve control actuator 340 with angular end 340^a carrying roller 360.

Herein the lower and upper heads include auxiliary intake passages 370 each arranged to be connected to a pressure source of coolant such

as compressed air, water, mist, steam or the like. Each is controlled by valve 371 carried by stem 372 associated with valve closing spring 373 as shown.

The lower auxiliary intake valve is directly actuated by member 340 engaging lower valve stem 372 to open the lower auxiliary intake when the piston is near the upper end of the stroke. The lower end of the cylinder is cooled and scavenged.

When the piston approaches the lower end of the cylinder 310, the arm 340 engages an angular end of tappet rod 374 and said rod is lowered to open upper auxiliary intake valve 371 for similarly cooling and scavenging the upper end of cylinder 310. In this form of the invention the ignition plugs are disposed centrally between the intake valves in each head but to one side thereof if necessary for clearance.

Operation of all forms of the invention are essentially the same except where noted hereinbefore. This invention, if desired, may be readily adapted to diesel type operation whenever desired.

While the invention has been illustrated and described in great detail in the drawings and foregoing description, the same is to be considered as illustrative and not restrictive in character.

The several modifications described herein as well as others which will readily suggest themselves to persons skilled in this art, all are considered to be within the broad scope of the invention, reference being had to the appended claims.

The invention claimed is:

1. In a dual acting, two-cycle engine having an elongated cylinder and a single piston therein, the combination of two heads closing opposite open ends of said cylinder, a piston rod connected to the piston, a connecting rod having crank connection to the engine crank shaft, an intake poppet valve in each head, common exhaust valve porting disposed approximately mid-way between the open ends of the cylinder, the piston being reciprocable beyond said porting and towards each of the heads for power impulse application to the crank shaft for each stroke of the piston, and means operable by the rod for selective actuation of said valves, said means comprising a solenoid for each valve, and switch means selectively controlling said solenoids, active elements of said means being movable by said rod.

2. An engine as defined by claim 1 wherein said switch means is of dual character, each of said dual portions comprising a pair of series connected switches, one being twice closable in rod reciprocation and the other being normally closed and rod opened, and means delaying closure of said other switch until said one switch has been closed and opened for the second time by said rod.

3. In a dual acting, two-cycle engine having an elongated cylinder, and a single piston reciprocable therein, the cylinder having exhaust porting equidistant from the ends, the combination of heads closing opposite ends of the cylinder, a rod for said piston and passable through at least one of the heads, an intake valve in each head and normally constrained to closed position, a rocker arm for opening each valve, and a single means reciprocable by said rod in the movement thereof and having dual contact with each of the rocker arms, but one of such contacts being effective for valve opening purposes.

4. In an engine as defined by claim 3 an auxiliary valve in each head normally constrained

to closed position and for the purpose described, independent actuators for each auxiliary valve, and a single means for actuating the actuators selectively near the ends of the piston stroke and carried by said rod.

5. An engine as defined by claim 3 wherein said last mentioned single means and the first mentioned single means are the same element.
